UNITED STATES PATENT OFFICE.

DONALD S. MULLIN, OF PITTSBURGH, PENNSYLVANIA.

METHOD OF HANDLING MATERIAL.

Application filed March 5, 1925. Serial No. 13,126.

To all whom it may concern:

Be it known that I, DONALD S. MULLIN, a citizen of the United States, residing at Pittsburgh, county of Allegheny, and State 5 of Pennsylvania, have invented a new and useful Improvement in Methods of Handling Material, of which the following is a full, clear, and exact description.

The present invention relates broadly to 10 material handling, and more particularly to an improved method of effecting removal of a layer of surface material, such as frequently referred to as overburden, to permit access to a sub layer or stratum of coal 15 or other desirable material.

At the present time, it is customary in the art to which the present invention relates to run a track substantially parallel to the edge of the overburden to be removed, 20 and preferably a few feet therefrom, to safeguard the track in the event of slides or the like. Thereafter, a large stripping tool, which may be in the form of a steam shovel, is positioned beside the track at a 25 point sufficiently removed laterally therefrom to provide the desired clearance between the track and the side of the tool. This tool is then operated, and the removed 30 waste material or overburden is carried to a point on the opposite side of the track, and usually initially deposited at a distance representing substantially the maximum reach of the shovel, where a shovel is 35 the type of tool being utilized.

It has heretofore been considered poor 40 practice to permit the pile of waste material to be in advance of the shovel. As the waste material is in the form of a ridge having sloping sides representing approximately the angle of repose of the material, it is obvious that the peak of the ridge is 45 considerably higher than the average top level of the overburden. This requires the shovel arm to be fully extended for each dumping operation, in order to raise the same to the peak of the ridge each time. This operation represents an actual elevation 50 of every cubic foot of material being handled to a point above the point from which it was excavated. Due to the relative positions of the shovel arm and the shovel boom, when the shovel arm is fully extended, the cables utilized for hoisting 55 purposes, exert a tremendous pull inwardly on the shovel arm, while the shovel operating motor is acting in opposition to this

pull. The necessary effect is to strain all the operating parts of the entire apparatus to substantially the point of maximum endurance. This is obviously poor practice, 60 and inevitably results in an exceedingly high operating cost and upkeep.

Furthermore since the shovel is always dumped at a point substantially opposite or slightly in back of the center of rotation of 65 the shovel, the shovel necessarily swings through an average angle for each dumping operation of greater than 90°. This represents unnecessary time for the swing, unnecessary power expenditure, particularly as 70 the shovel arm is fully or substantially fully extended, and unnecessary wear not only on the circle track but also on the other operating parts of the apparatus.

This manner of discharging material, in 75 addition to being both wasteful and costly, is extremely hazardous, due to the fact that ordinarily a number of operatives are positioned between the excavating tool and the ridge, thereby placing them directly in the 80 path of falling particles, or rolling stones which frequently cause a great deal of damage.

My present invention has for certain of 85 its objects improved efficiency in the handling of such waste material, decreased time in the handling of each unit of material, increased tonnage in the material being handled together with a material saving in the cost not only of operation but also of 90 upkeep. In accordance with the present invention, the improved method of operation also results in measurably greater safety to the operatives and equipment, with far less likelihood of any injury to either. In 95 actual practice, I have found that it is possible to utilize an 8 yard shovel, for example, with apparatus designed for a 6 yard shovel, due to the fact that my improved method does not subject any of the 100 working parts to the tremendous strains to which they have heretofore been continuously subjected in operation.

Also, according to prior practice, it has 105 seldom, if ever, been possible to effect a complete shovel cycle, representing travel of the shovel from the point at which the digging is initiated to the point of dump and return to the point initially referred to, in less than 45 seconds, the average time being about 54 seconds. In accordance with 110 my improved invention I have frequently

made complete cycles of operation in as low as 20 seconds, under exactly the same operating conditions with the same material and the same equipment, my average time for 5 each cycle being approximately 40 seconds. This represents a material saving in time, wear and strain on the hoist cables especially, in addition to the saving and wear on other parts of the equipment, and also 10 represents an actual saving in power of approximately 60%. Obviously, this involves an increase in the number of cubic yards of material handled per tool with a consequent decrease in the entire cost of operation commensurate therewith.

Exactly the same principles and advantages as those heretofore pointed out are obtained with other types of material handling apparatus such, for example, as 20 locomotive cranes either of the clam shell or orange peel bucket variety, with drag line apparatus or with gantry cranes or the like constructed for handling material of the character herein contemplated. It will be understood, therefore, that throughout 25 the specification and claims I utilize the expression "tool" in its generic sense as definitive of a structure capable of performing the functions contemplated irrespective 30 of the construction of such tool or its special commercial designation.

In the accompanying drawings I have shown for purposes of illustration only, 35 certain preferred embodiments of the present invention, it being understood that the drawings are largely diagrammatic and that they do not represent or define the limits of my invention as changes in the construction of the apparatus and operation 40 thereof may be made without departing either from the spirit of the invention or scope of my broader claims.

In the drawings:

Figure 1 is a diagrammatic top plan view 45 representing one method of handling material in accordance with the present invention by the utilization of a tool of the shovel type;

Figure 2 is a side elevation illustrating a 50 portion of the operation shown in Figure 1, and.

Figure 3 is a diagrammatic view representing the operation of a tool, for example, 55 of the drag line type.

In carrying out the present invention, there may be utilized the usual track T adapted to run substantially parallel, and in spaced relationship, to one edge of the material M to be removed, and usually referred to as overburden. In other cases, the track may be entirely dispensed with, and positioning of the equipment modified accordingly.

Where the track is provided, the tool 2 60 is positioned at one side thereof with its

axis of rotation 3 at some predetermined point determined for the most efficient operation. Where the tool is of the shovel type, it will be positioned in such manner that the shovel arm 4 carried by the boom 5 may be substantially entirely retracted in effecting the initial cuts from the overburden. In Figure 1 of the drawings, there is illustrated a curved dotted line 6 representing the point at which, by a previous 70 positioning of the tool, the overburden was removed. The corresponding circle 7, in full lines, represents the point to which the material or overburden will be removed by the positioning of the tool illustrated in 75 Figure 1. In accordance with preferred practice, the distance between these circles 80 will be in the neighborhood of 8 feet.

In carrying out the present invention, the tool will initially be operated to remove 85 that portion of the material indicated as first cut in Figure 1 of the drawings, this being the portion of the material at the outside corner of the overburden and similarly designated in Figure 2. This operation is 90 repeated until the complete upper layer or bench B is entirely removed throughout the width of the strip of overburden which is being operated upon by the tool. After each 95 cut or shovelfull, the shovel arm is retracted, and the entire boom thereupon swung in 100 a counter clockwise direction as viewed in Figure 1 to bring the shovel over a point P on the opposite side of the track T, where such track is provided. It will of course 105 be understood that where the track is not utilized, a corresponding position may be determined upon. In Figure 1, the curved line 8 represents the approximate shape of the end of the ridge of waste material, the peak thereof being indicated by the line 9. The line 10 extending substantially parallel 110 to the line 9 represents the peak of a ridge of waste material removed in a previous stripping operation.

The disposing of material at the point P is continued until such time as the material, building up in accordance with the natural laws of repose of such material extends to the limit line 11 which it is desired to have 115 this outer edge of the material reach. Thereafter, successive cuts of material will be discharged at points P², P³, etc. continuously along the dotted line 12.

From a careful consideration of the diagrammatic illustration in Figure 1 it will be apparent to those skilled in the art that the deposit initially at the point P involves a radical departure from prior practice and is responsible for many advantages inherent 125 in the handling of material in accordance with the present invention. In the first place, the peak of the pile of material coinciding with the point P is materially lower than the corresponding point from which 130

the material is excavated by the tool. This means that the tool is not required to raise any of this material above the point of its removal in order to effect discharge thereof. Furthermore, this initial comparatively small pile of material forms a protective barrier intermediate the main peak of the material and the tool, effectively preventing large rocks and the like from subsequently 5 rolling onto the workmen, it being apparent that points P^2 , P^3 , etc. represent progressive points beyond the peak of the ridge established by each preceding dumping operation. This insures the rolling of the 10 discharged material away from the tool instead of toward the tool in the manner heretofore inherently necessitated.

After the first bench B has been entirely removed, during which process the shovel 20 arm is always in substantially its retracted position before referred to as distinguished from a forwardly crowded position as represented by present day operations, a series 25 of second cuts as correspondingly indicated in Figures 1 and 2 will be removed until a second bench B' is carried away and discharged.

During removal of the second bench, the shovel arm is at a substantially intermediate 30 position, at which there is no appreciable strain on the apparatus and at which it may be easily manipulated and swung as required. Thereafter the third bench B^2 will be removed by a series of third cuts 35 correspondingly indicated in Figures 1 and 2. To effect the removal of this portion of the overburden, the shovel will be at a more extended position, not representing, however, its maximum extension. As the 40 material of benches B and B' has been removed, the point of discharge has gradually travelled up the curved line 12 to a point adjacent the peak 9. This peak 9, however, has not been reached and therefore it is 45 obvious that it has not been necessary to raise any of this previously removed material above the normal level of the overburden in order to effect its discharge at the desired point. As the third bench 50 approaches complete removal, the peak 9 is approximated so that theoretically for the last shovelfull of material only will it be necessary to exert the apparatus to the extent required to deposit the same at a point 55 corresponding to the elevation of the peak. Prior to this final shovelfull, the tool has been operating within normal limits of operation without substantial strain and with 60 corresponding ease of manipulation accompanied with a minimum power consumption.

The operation before described involves another advantage in that for the initial cuts of material the swing of the tool is through a comparatively small angle, this 65 being necessarily the case as the deposit is

initiated at a point closer to the point of removal than is the case, in accordance with established practice, where this material is carried each time to the peak, discharged thereon, and permitted to roll to its natural 70 position of rest. As an actual matter of practice, the included angle of swing for these initial cuts is in the neighborhood of only 15° as contrasted with an included angle of 90° or more necessitated in accordance with prior practice. It will readily be seen that this means the removal of an equivalent amount of material with a minimum power consumption and wear on the 75 equipment.

After all of the benches have been removed, the tool will be moved ahead along its established line of operation to a point substantially 8 feet in advance of that previously occupied. This in turn will bring 80 the new point of discharge p to a point substantially 8 feet in advance of the point P. The operations and cycles before referred to in connection with the preceding 85 operation will then be repeated, and this will be carried out until the entire 90 amount of the overburden has been effectively displaced and deposited.

In Figure 3 of the drawings I have indicated diagrammatically the contour of a 95 pile of waste material 14 of the type which will be formed by a tool 15 of the drag line type, it being understood that the only difference in operation is that represented by a convex line of deposit for the shovel 100 type of excavator as contrasted with a concave line of deposit 16 for a tool of the drag line type.

Furthermore, the present invention is distinguishable from methods heretofore practiced in that it represents a discharge 105 of material initially in the most convenient point as distinguished from the universally established practice of always carrying the material to the highest point of discharge 110 which necessarily is the point furthest removed from the material in its original location. The advantages of the invention therefore are those which are inherent in the conservation of power and the decrease 115 in upkeep represented by an effective handling of material in such manner that the majority of the material does not have to be raised above the plane of its removal and in which the operation is such that 120 previously deposited material tends to safeguard both the equipment and the operatives.

These advantages also represent a corresponding saving in wear and strain on the 125 equipment, a decrease in the upkeep cost of the equipment as well as the reduction of the power consumption to a minimum.

I claim:

1. The method of handling material, com- 130

prising moving a stripping tool to a predetermined position, initially operating said tool to remove an upper bench of the material, carrying said material by the stripping tool laterally from the point of removal, and depositing said removed material from a point not higher than the point from which it was removed, substantially as described.

2. The method of handling material, comprising moving a stripping tool to a predetermined position, initially operating said tool to remove an upper bench of the material, depositing said removed material from a point not higher than the point from which it was removed, and thereafter progressively depositing said material at points rearwardly of said initially deposited material with respect to the position of the stripping tool, substantially as described.

3. The method of stripping material, comprising moving a stripping tool to a predetermined position, initially operating the same to remove an upper bench of the material, depositing said material from a point not higher than the point from which it was removed, removing successive benches of such material, and discharging successively removed material at a point beyond the initial point of discharge, substantially as described.

4. The method of stripping material, comprising moving a stripping tool to a predetermined position, initially operating the same to remove successive cuts in an upper bench of the material, carrying said material by the stripping tool laterally from the point of removal, and depositing said material from points not higher than the point from which it was removed, substantially as described.

5. The method of stripping material, comprising moving a stripping tool to a predetermined position, initially operating the same to remove successive cuts in an upper bench of the material, and depositing said material from points not higher than the

point from which it was removed, the points of discharge for the material being progressively further from the tool than the point of initial deposit, substantially as described. 60

6. The method of stripping material, comprising moving a stripping tool to a predetermined position, initially operating the same to remove an upper bench of material, and depositing said material by the stripping tool at a point opposite the point of removal and in advance of the axis of rotation of the stripping tool, substantially as described.

7. The method of stripping material, comprising moving a stripping tool to a predetermined position, initially operating the same to remove an upper bench of material, depositing said material at a point opposite the point of removal and in advance of the axis of rotation of the stripping tool, and thereafter removing successively lower benches of material, and moving the points of deposit rearwardly as successive benches are removed, substantially as described. 65 70

8. The method of stripping material, comprising moving a stripping tool to a predetermined position, initially operating the same to remove an upper bench of material, depositing said material at a point opposite the point of removal and in advance of the axis of rotation of the stripping tool, and thereafter removing successively lower benches of material, and moving the points of deposit further from the axis of rotation 75 80 of a tool, substantially as described.

9. The method of removing material, comprising depositing the removed material at points progressively beyond the point of initial deposit, whereby the material initially deposited serves as a barrier intermediate the tool and the deposited material, substantially as described. 85

In testimony whereof I have hereunto set my hand.

DONALD S. MULLIN.
